UNITED STATES PATENT OFFICE.

WILLIAM J. ASHER, OF COLORADO SPRINGS, COLORADO.

DOFFING APPARATUS FOR MANGLES.

Application filed December 2, 1921. Serial No. 519,471.

To all whom it may concern:

Be it known that I, WILLIAM J. ASHER, a citizen of the United States, and residing at Colorado Springs, El Paso County, State 5 of Colorado, have invented certain new and useful Improvements in Doffing Apparatus for Mangles, of which the following is a specification.

This invention relates to laundry ironing 10 machines or mangles of the rotary drum type and particularly to the doffing mechanism for continuously removing the work from the rotating drum.

One object of the invention is to provide 15 an improved bar for supporting the doffing knives which may be quickly and easily removed from the machine for the purpose of adjusting the knives or replacing one or more of the doffing tapes. To this end the 20 doffing bar is mounted in the frame in a novel manner so that it may be withdrawn without difficulty from its operative position, to a position in which the knives may be reached by the operator and replaced with 25 ease. By thus displacing the doffing bar renewal of the doffing tapes may also be accomplished. Another feature of the invention resides in the novel manner in which the doffing knife supporting arms are pivot- 30 tally connected to the doffing bar. Additional objects and advantages of the present invention reside in the simple construction of the doffing bar and knife holding arms, enabling the same to be made more cheaply 35 than theretofore.

The invention will be fully set forth in the following description when taken in connection with the accompanying drawings in which:

40 Figure 1 is a section through a portion of a rotary drum mangle showing the improved doffing bar construction;

Figure 2 is a section on the line 2—2 of Figure 1;

45 Figure 3 is a plan view of one end of the doffing bar showing the means for supporting this end in the frame; and

Figure 4 is an enlarged sectional view 50 through the doffing bar and a doffing knife.

The type of mangle to which this invention is especially adapted to be applied is described and illustrated in my Patent No. 1,354,871 dated October 5, 1920. It will be understood, however, that the invention is 55 applicable to other types of rotary drum mangles and is not limited in its application

to mangles having the exact construction of the mangle disclosed in the application mentioned.

In the drawings a portion of one side of 60 the frame of the mangle is indicated at 10 and the drum 11 is mounted for rotation in this frame. Rollers 12, 13 and 14, the axes of which are parallel to the axis of the drum, are mounted at one side thereof and extending 65 around the rollers 12 and 13 and around the drum is an endless apron 15 which moves with the drum in the direction of the arrow and serves to hold the work against the drum in its rotation. Rollers 13 and 14 are 70 supported by levers L and M respectively, these levers being in turn pivoted on the frame and adapted to be manually manipulated to raise and lower the rollers, as described in my prior patent. The work is 75 fed in between the roller 12 and the short endless doffing tapes 16 which pass under the wedge-shaped doffing bar 17 and over the roller 14. After having passed around the drum the work is removed therefrom by 80 the doffing knives 18 in well known manner, and the doffing knives are kept clear by the action of doffing tapes 16 and the endless apron 15 which grip the work between them and carry it around the roller 13. It is 85 then carried over the machine to the opposite side thereof on the upper turn of the endless apron 15.

The doffing knives 18 are T-shaped and have their stems secured to knife carrying 90 arms 19 by screws 20. Small screws 21 are provided for adjusting the angle of the doffing knives relatively to the arms 19, so that their edges may bear equally against the drum 11. Rectangular openings are left 95 between the stems of the knives and arms 19 and through these openings the doffing tapes 16 extend.

The doffing bar is triangular or wedge-shaped in cross section and is provided with 100 the upwardly projecting flange 17' the inner face of which comprises an abutment against which the outer or rear edge of each of the knife holding arms 19 is adapted to bear. Each of the knife holding arms is 105 formed with a recess in its rear edge at one end, and pins 23 secured to and extending upwardly from the upper surface of the doffing bar adjacent the flange 17' fit loosely in these recesses and comprise means 110 for separating and preventing longitudinal displacement of the arms 19. In the opera-

tion of the mangle the arms are free to move or pivot about their rear edges to allow the knife edges to move inwardly or outwardly to compensate for inequalities in 5 the surface of the rotating drum.

The doffing bar is supported at its ends (only one of which is illustrated) in brackets 24 secured to the frame, each bracket having an inwardly extending flange 25 and 10 an aperture 26 adapted to receive the pin 27. The flange 25 is cut away as shown at 28 but has upper and lower bearing surfaces 29 and 30 respectively, against which one face of the doffing bar rests. Another face 15 of the doffing bar rests against the flat face 31 of the pin 27 and the end of the bar is adapted to engage the inwardly facing shoulder 32 of the pin 27, when the bar is in position, thereby locking the pin in the 20 aperture 26. The bar is therefore wedged by its own weight in between the flange 25 and pin 27, which together comprise a supporting cradle.

The bar may be removed in either of 25 two ways, by lifting the rollers by means of the levers and then lifting the bar from its supporting cradle, or by removing the pins 27. In removing the bar by the second method mentioned it is only necessary to 30 raise it slightly to disengage its ends from the shoulders 32 of pins 27, which may then be easily withdrawn from recess 26. After the removal of the pins the bar may be lowered or drawn outwardly away from 35 the drum for the purpose of replacing one or more of the doffing tapes 16. For the purpose of facilitating the removal of the pin 27 an aperture 33 is provided in the bracket so that an instrument may be inserted therethrough to contact with the end 40 of the pin to force it from the socket 26.

By employing the above described means for supporting the bar in the frame it can be quickly removed, and as quickly replaced 45 in position. The shape of the bar with the projecting flange 17' is such that it may be made of cold rolled steel instead of cast steel, as heretofore; the pins 23 being inserted after the bar has been cut to length 50 and avoiding the necessity of having special ears formed integral with or secured to the bar for the purpose of pivotally supporting the arms 19, which construction has been heretofore used. It will be obvious to those 55 skilled in the art that the design and arrangement of parts of the invention may be varied and the invention is not limited therefore to the exact embodiment described.

Having thus described the invention what 60 I claim as new and desire to secure by Letters Patent is:

1. In a mangle, in combination, a frame, a rotary drum, doffing means for removing the work from the drum, including a doffing 65 bar having its axis parallel to the axis of

the drum, and means for removably supporting the bar in the frame, said means including a two-part cradle upon which one end of the bar rests, one portion of the cradle being rigidly secured to the frame and the 70 other portion being detachably secured thereto so that it may be readily removed to allow the bar to be lowered.

2. In a mangle, in combination, a frame, a rotary drum, doffing means for removing 75 the work from the drum, including a doffing bar having its axis parallel to the axis of the drum and being wedge-shaped in cross section, and means for removably supporting the bar in the frame, said means including a 80 member rigidly secured to the frame and a member detachably secured to the frame, one end of the bar resting on and extending downwardly between both of said members and being supported thereby, the detachable 85 member being adapted to be readily detached so that the bar may be removed.

3. In a mangle, in combination, a frame, a rotary drum, doffing means for removing the 90 work from the drum, including a doffing bar 95 having its axis parallel to the axis of the drum, and means for removably supporting the bar in the frame, said means including a member rigidly secured to the frame and a pin fitting in an aperture in the frame, 100 said member and pin both extending laterally from the frame and adapted to jointly support one end of the bar, said pin and bar having mutually engaging portions whereby the pin is locked in supporting position 105 when the bar is resting thereon but is released when the bar is raised, whereupon it may be removed from the aperture and the bar lowered.

4. In a mangle, in combination, a frame, a 105 rotary drum, doffing means for removing the work from the drum, including a wedge-shaped doffing bar having its axis parallel to the axis of the drum, and means for removably supporting the bar in the frame, said 110 means including a flange extending laterally from the frame and pin spaced therefrom and removably supported in an aperture in the frame, the bar being wedged between said pin and flange and supported thereby 115 but adapted to be lowered when the pin is removed.

5. In a mangle, in combination, a rotary 120 drum, and means for doffing the work from said drum, said means including a bar having a substantially vertical abutment facing the drum, a pin secured to the bar in front of the abutment and extending vertically upwardly, and a knife carrying arm having its rear edge bearing against said abutment 125 and extending toward the drum, said arm having an aperture adapted to receive the upwardly projecting pin but being freely removable at all times from said bar.

6. In a mangle, in combination, a rotary 130

drum, and means for doffing the work from said drum, said means including a bar having an abutment facing the drum, a knife supporting arm having a portion bearing 5 against said abutment and having a notch in one end, a pin secured to said bar and extending through said notch, and a second pin secured to said bar and positioned adjacent the opposite end of said arm.

10 7. In a mangle, in combination, a rotary drum, and means for doffing the work from

said drum, said means including a bar having an abutment facing the drum, a series of knife supporting arms having portions bearing against said abutment and pins secured 15 to said bar and extending between the adjacent ends of the knife supporting arms to hold the same in spaced relation.

In testimony whereof I hereunto affix my signature.

WILLIAM J. ASHER.
